(21) Appl. No.: **29/270,692**

(57) **CLAIM**

(22) Filed: **Jan. 3, 2007**

The ornamental design for an electrical contact for use in a plating apparatus, as shown and described.

(51) **LOC (8) Cl.** **13-03**

DESCRIPTION

(52) **U.S. Cl.** **D13/148**

FIG. 1 is a perspective view of an electrical contact for use in a plating apparatus in accordance with the present design;

(58) **Field of Classification Search** D13/133,

FIG. 2 is a front view thereof;

D13/148, 154, 184, 199; 439/865, 868, 877-891,
439/894

FIG. 3 is a back view thereof;

See application file for complete search history.

FIG. 4 is a plan view thereof;
